18,373:

Design No. 18,373, dated June 5, 1888.

UNITED STATES PATENT OFFICE.

FREDERICK MITCHELL, OF BROOKLYN, NEW YORK.

DESIGN FOR A CALENDAR.

SPECIFICATION forming part of Design No. 18,373, dated June 5, 1888.

Application filed March 17, 1888. Serial No. 267,567. Term of patent 7 years.

To all whom it may concern:

Be it known that I, FREDERICK MITCHELL, of Brooklyn, in the county of Kings and State of New York, have invented and produced a new and original Design for a Calendar, which is shown in the accompanying photographic illustration. The illustration shows a ship's steering-wheel having rim and spokes, but all the spaces between the latter are covered or closed, save one, which is left open. The standard or support of the wheel rests on a square base, and the helmsman holding the wheel also stands on this base, a portion of his body being concealed by the wheel.

I claim—

The design for a calendar, consisting of the representation of a ship's steering-wheel having a rim and spokes, the spaces between the latter being shown closed, save one, which is open, and the figure of a helmsman holding the said wheel and standing behind it and leaning forward, as shown. 15 20

FREDERICK MITCHELL.
